(57) **CLAIM**

The ornamental design for a quarter fender, as shown and described.

DESCRIPTION

FIG. 1 is a perspective view of a quarter fender according to our new design;

FIG. 2 is a top view of the quarter fender of FIG. 1;

FIG. 3 is a side view of the quarter fender taken from the left side of FIG. 1; and,

FIG. 4 is a front view of the quarter fender of FIG. 1.

The bottom and rear of the quarter fender is unornamented. FIGS. 1-4 illustrate a first embodiment of our novel design suitable for use on the left side of a vehicle. Our novel design also includes a second embodiment suitable for use on the right side of a vehicle, which is mirror symmetrical to FIGS. 1-4 and therefore not separately illustrated.
